PHASE MODULATION

Murray G. Crosby, Riverhead, N. Y., assignor to
Radio Corporation of America, a corporation of
Delaware.

Application October 4, 1944, Serial No. 557,195

6 Claims. (Cl. 179—171.5)

1 This application relates to phase modulation of wave energy in accordance with program and other voice signals. In particular this application concerns operation of phase modulators such as disclosed in my U. S. Patent #2,085,739, dated July 6, 1937; U. S. Patent #2,165,229, dated July 11, 1939; Patent #2,238,249, dated April 15, 1941; Patent #2,230,231, dated February 4, 1941; and Patent #2,230,232, dated February 4, 1941.

The general object of my invention is improved operation of phase modulators.

A more detailed object of my invention is to improve the efficiency of operation of phase modulators by fuller use of the modulation power and of the channel in which the modulator is operating.

In describing my invention in detail reference will be made to the attached drawings wherein

Fig. 1 illustrates diagrammatically and mostly by rectangle a phase modulation system with the essential features of my invention.

Fig. 2 illustrates in a similar manner a receiver for the modulated signal sent out by the transmitter of Fig. 1.

Fig. 3 illustrates the character of the phase modulation transmitter of unit 10 of Fig. 1.

The invention is applicable to true phase modulators such as illustrated by certain of the patents referred to above, and to corrected phase modulators such as disclosed in Patent #2,085,739. In this phase modulator the modulation is modified in accordance with its frequency and used to modulate the frequency of an oscillation generator.

In the description which follows I have used as an example a phase modulator of the corrected frequency modulation type. To those skilled in the art it will be apparent that the principle of my invention is applicable in like manner to true phase modulators.

In the present frequency modulation broadcasting systems the lower modulation frequencies are passed with their normal amplitude, and the higher modulation frequencies are emphasized in accordance with their frequency. This operation on the higher frequencies converts the modulation into phase modulation so the system is FM with respect to the modulation of low frequency, and PM for the modulation of higher frequency. This requires some reduction of modulation level at the transmitter but there is an overall improvement due to noise rejecting by the de-emphasis network at the receiver. For a complete analysis of the signal-to-noise ratio gain effected by the use of pre-emphasis and de-

emphasis, reference is made to my article entitled, "The service range of frequency modulation," published in the January 1940 issue of RCA Review.

5 The improvement depends entirely on the nature of the modulation, since pre-emphasis of the higher modulation frequencies is permissible only because they are of sufficiently low amplitudes (relatively) that they can be boosted without unduly increasing the peak modulation level.

It will be noted that this improvement depends directly upon the nature of the modulation material, i. e., the relatively low amplitude of higher frequency modulation components.

10 It has occurred to me that considerable advantage would result from the use of phase modulation at the transmitter since this would entail pre-emphasis of the higher modulation frequencies as viewed from a frequency modulation standpoint. The band width occupied by the transmitter is the governing limitation. A study of the degree of phase modulation which may be applied without the effective frequency deviation of the phase modulation transmitter being made greater than the peak deviation of an equivalent frequency modulation system was made. A study was then made of the degree of phase modulation which may be applied without the effective frequency deviation exceeding the assigned band width. An arrangement as shown in Fig. 1 was used.

15 In Fig. 1, 10 indicates a phase modulation transmitter such as disclosed in the patents listed above. 20 is radiating means connected thereto. 20 is a two-pole two-way switch for connecting the source 22 or the source 28 to the modulator in the transmitter 10. The source 22 supplies oscillations of about a single frequency and of a frequency within the frequency spectrum covered by the program voltages or currents from the modulation source 28. 30 is a variable gain amplifier, and 33 is a peak-reading volt meter. 40 is a monitor receiver connected with an oscilloscope 42 on which the degree of modulation may be observed.

20 The band width of the phase modulated wave emitted by 10 is determined by the effective frequency deviation of that wave. For sinusoidal modulation, the effective frequency deviation, F_d , is given by:

$$F_d = \phi F_m \quad (1)$$

25 where ϕ is the phase deviation in radians and F_m is the frequency of the modulating wave. To determine the band width for the test tone the max-

imum value of F_m is substituted in (1). For instance, if F_m (max) were 15,000 cycles, and $\phi=5$, $F_d=75,000$ cycles. Hence the band width for the phase modulated wave resulting from use of the test tone is 150,000 cycles. As described in my article, "Communication by phase modulation," Proc. I. R. E., February, 1939, the signal-to-noise ratio gain for the system of this example is equal to the phase deviation in radians or 5.

The degree of frequency deviation applied to 10 may be measured on monitor receiver 40 which gives an output proportional to frequency deviation. When the proper degree of modulation is applied, the indication of modulation input meter 33 is noted.

When program modulation is applied to 10, I have found that a considerably greater level may be applied across the terminals of the modulator and meter 33 before the proper frequency deviation is indicated at monitor receiver 40. In other words, the level fed to 33 may be emphasized to a degree higher than the normal tone modulation input. My experiments have shown the magnitude of this increase in level to be approximately equal to F_m (max)/1500 for an audio band of 15,000 cycles.

From the results of the experiments, for purposes of determining the effective frequency deviation of the phase modulated wave it may be seen that the effective frequency of the complex program modulating wave is 1500 cycles. Hence in applying the formula, $F_d=\phi F_m$, the value of F_m is taken as 1500 cycles when program modulation is used. For the case of the example quoted above, a phase deviation of 5 radians would give an effective frequency deviation of 5 times 1500 or 7500 cycles. Thus to increase the phase deviation to produce the required 75,000 cycles frequency deviation of the example, the phase deviation must be increased 75,000/7500 or 10 times.

This increase in level applied to the phase modulation transmitter represents an additional signal-to-noise ratio gain over and above the factor equal to the phase deviation in radians. The total gain is thus

$$\frac{\phi \times F_m \text{ (max)}}{1500}$$

The additional gain is brought about by the fact that program modulation is so distributed in the audio spectrum that it produces a lowered effective frequency deviation when applied to a phase modulation transmitter. This can be seen by a reference to Fig. 3 which shows a phase modulation transmitter of the corrected frequency-modulation type as described in my U. S. Patent #2,085,739. It will be noted that this phase modulator is a frequency modulator with an input network which raises the amplitude of the modulation frequencies in accordance with their frequency. Hence the effective frequency deviation of a phase modulated wave is proportional to the modulating frequency. When a program wave is applied to the equalizing network, the energy in the wave is reduced since most of the energy is in the lower audio frequencies. This reduces the effective frequency deviation of the phase modulated program wave. As a result, additional modulation may be applied to the phase modulator input to bring the band width of the wave up to the normal band width of the phase modulation receiver.

In accordance with my invention then the test tone of 15,000 cycles per second from 22 is ap-

plied as modulation to the transmitter 10 through switch T, and the tone amplitude brought up for full modulation of the carrier, as indicated on the oscilloscope 42. The reading on the meter V for full modulation as denoted on the target of the oscilloscope 42 is noted. Then the switch T is reversed and the program material from source 28 is applied to the terminals of the modulator 10 and across meter 33. In usual FM broadcast systems and operation known heretofore, the modulation material amplitude is made such that the reading on the peak volt meter V is the same as the reading described above, taken when tone from the source 22 was applied. If meter V is the root-mean-square type of meter, consideration has to be given to the crest factor of the program wave. The crest factor is from 6 to 10 decibels so in the usual FM systems not using pre-emphasis, program input is made 6 to 10 decibels lower than tone input as read on an R.-M.-S. meter. This adjustment gives equal peak voltages of the tone and program input.

In accordance with my invention, however, the modulation material applied has its amplitude boosted, by say a variable gain amplifier in 30, so that the peak voltage at the modulator input and across meter V not only equals the reading taken as described above when tone was applied, but exceeds the said meter 33 reading by a factor

$$\frac{F_m \text{ (max)}}{1500}$$

In a particular example investigated F_m was 15,000 cycles per second, giving an improvement factor of 10 times. This resulted in considerable improvement in signal-to-noise ratio in the system.

The modulation meter at 40 and 42 may be of any approved type, and will not be described in detail herein. Receiver 40 consists of a conventional frequency modulation receiver which gives a known output for a given frequency deviation applied at the input. This known output is read on oscilloscope 42, which has its deflection calibrated in frequency deviation. The receiver may be calibrated by the use of a frequency modulated generator. The frequency modulated generator may be calibrated by the method described in my U. S. Patent #2,293,022, issued August 11, 1942.

The phase modulation receiver of Fig. 2 may be of any approved type, but is preferably of the type disclosed in my U. S. Patent #2,229,640, dated January 28, 1941, or Patent #2,230,231, dated February 4, 1941, or in Patent #2,230,232, dated February 4, 1941.

In actual operation there is room for considerable variation in the factor. The complex program wave is exceedingly variable and judgment is required to determine its peak value. As an example, we have the disagreement as to the crest factor of program modulation—some broadcast engineers use 6 decibels and others use as high as 10. Hence a quantity which depends upon the peak voltage of the program wave, as F_m (max)/1500 does, can not be precisely designated. Someone else's judgment might choose the values to make the quantity F_m (max)/1000 or F_m (max)/2000.

4
70 I claim:

1. In combination, an angular modulator including a circuit wherein wave energy of carrier wave frequency flows and a source of modulating currents representing a program arranged to be coupled with said circuit to modulate the an-

angular velocity of the wave energy in accordance with the currents, a source of oscillations, of substantially single frequency, arranged to be coupled to said circuit to modulate the angular velocity of the wave energy in accordance with the oscillations, means for indicating the amplitude of the oscillations required to accomplish about 100% modulation of the carrier energy by the oscillations, and means for increasing the amplitude of the modulation currents beyond the amplitude of the oscillations when the modulation currents are used to modulate the wave energy.

2. The method of operating a modulation system having means for modulating the angular velocity of wave energy by program currents which includes these steps, generating oscillations of a substantially single frequency within the program current frequency spectrum, modulating the angular velocity of said wave energy by said oscillations and increasing the degree of modulation to about 100%, then measuring the amplitude of the oscillations, increasing the amplitude of the program currents materially above the amplitude of the oscillations, and modulating the timing of the wave energy by the modulation currents of increased value.

3. The method of operating a phase modulation system having means for modulating the phase of wave energy by program currents which includes these steps, generating oscillations of a substantially single frequency within the program current frequency spectrum, modulating the phase of said wave energy by said oscillations and increasing the degree of phase modulation of the wave energy by the oscillations to about 100%, producing an indication of the amplitude of the oscillations required to produce said phase modulation, producing an indication of the amplitude of the program currents, increasing the amplitude thereof until said last mentioned indication is materially above the said indication of the amplitude of the oscillations, and modulating the phase of the wave energy by the amplified program currents.

4. The method of operating a phase modulation system having means for modulating the phase of wave energy by program currents which includes these steps, generating oscillations of a substantially single frequency within the program current frequency spectrum, modulating the phase of said wave energy by said oscillations to about 100% modulation, producing an indication of the amplitude of the oscillations required to produce said about 100% modulation, producing an indication of the program current amplitude and increasing the amplitude of the program

currents until said last named indication exceeds said first named indication by a factor of the order of

$$\frac{F_m \text{ (max)}}{1500}$$

where $F_m \text{ (max)}$ is the program maximum current frequency, and modulating the wave energy by the modulation currents of increased value.

5. In combination, a phase modulator including a circuit wherein wave energy of carrier wave frequency flows and a source of modulating currents representing a program arranged to be coupled with said circuit to modulate the phase of the wave energy in accordance with the currents, a source of oscillations of substantially single frequency, arranged to be coupled to said circuit to modulate the angular velocity of the wave energy in accordance with the oscillations, means for indicating the amplitude of the oscillations required to accomplish 100% modulation of the carrier energy by the oscillations, and means for increasing the amplitude of the program modulation currents by a factor of the order of

$$\frac{F_m \text{ (max)}}{1500}$$

beyond the amplitude of the oscillations when the program modulation currents are used to modulate the wave energy where $F_m \text{ (max)}$ is the maximum frequency of the program current.

6. The method of improving the signal-to-noise ratio of a phase modulation system which transmits a complex modulating wave having a maximum frequency which includes, modulating the angular velocity of a carrier wave by a sinusoidal wave of a frequency about equal to said maximum frequency of said complex modulating wave, modulating the angular velocity of said carrier wave by the complex modulating wave, and controlling the degree of said last angular velocity modulation so that the effective peak frequency deviation of the carrier is made equal to the effective peak frequency deviation of said carrier when the same is being angularly velocity modulated by said sinusoidal wave.
